APPLICATOR FOR APPLYING INSULATION
TO WIRE

Philip V. Kessler, Phillipsdale, and John B. Moss,
Providence, R. I., assignors to Kennecott Wire
and Cable Company, Phillipsdale, R. I., a cor-
poration of Rhode Island

Application March 30, 1946, Serial No. 658,544

5 Claims. (Cl. 91—53)

1

The present invention relates to improvements in devices for applying coatings of insulating material to electric wires, and relates more particularly to devices of the character referred to whereby viscous insulating materials may be applied to electric wires. While the present invention is primarily designed to effect the application of coatings of viscous insulating materials to very fine wires, the said applicator is available for coating coarser wires.

One of the objects of the present invention is to provide a superior applicator of the character referred to which will reliably apply one or more continuous coating of viscous insulating material to a wire, and which is economical to produce and maintain.

Another object of the present invention is to provide a superior applicator which includes two members or portions which cooperate to provide one or more wire-receiving passages and which do not require difficult adjustment of the said members or portions with respect to each other in order to provide such passages.

A further object of the present invention is to provide a simple and effective applicator of the character referred to by means of which one or more coatings of viscous insulating material may be applied to a wire in such manner that substantially uniform distribution of the said material on the wire is assured.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken top or plan view of an applicator-assembly embodying the present invention with the supporting-means partly broken away;

Fig. 2 is an edge view of the showing of Fig. 1;

Fig. 3 is a fragmentary view of a portion of the two complimentary applicator-plates on a very much enlarged scale and showing a wire located therein but omitting the insulating material;

Fig. 4 is a broken vertical sectional view on substantially the scale of Fig. 3, and taken on the line 4—4 of either Fig. 1, or Fig. 3;

Fig. 5 is a broken top or plan view of a fragment of one of the complementary applicator-plates, detached; and

Fig. 6 is a similar view of the other applicator-plate, detached.

As shown, the applicator includes two cooper-

ating applicator-plates respectively designated by the reference characters 10 and 11 and normally held in edge-to-edge contact, as shown. The applicator-plates 10 and 11 are respectively secured to supporting plates 12 and 13 or other suitable support by means of screws 14 or their equivalent.

The applicator-plate 10 has the under portion of its inner edge beveled as at 15, in opposition to a bevel 16 on the companion applicator-plate 11. The arrangement of the respective bevels 15 and 16 of the applicator-plates 10 and 11 serves to provide in the under face of the assembly between the respective inner faces of the supporting-bars 15 12 and 13, an upwardly-and-inwardly converging V-shaped channel. It will be noted by reference to Fig. 2 in particular that the extents of the bevels 15 and 16 just referred to, are such as to leave the applicator-plates 10 and 11 with narrow parallel inner edges which abut one against the other.

In its inner edge the applicator-plate 10 is formed with eight (more or less) notch-like wire-receiving passages respectively designated by the reference characters 17a to 17h inclusive and intersecting the bevel 15. In the instance shown, the passages 17a to 17h inclusive correspond to each other save with respect to small differences in dimensions, and have their outer ends normally closed by the straight edge of the companion applicator-plate 11.

For purposes of example only, it may be assumed that the applicator-assembly is intended to apply repeated coatings of insulating material to the same wire such as the wire 18 indicated in Figs. 3 and 4. It may further be assumed that the wire 18 is #38 (American wire gauge) and therefore about .004" in diameter. Under the assumptions just noted the passages 17a and 17b may be about .0042" in width (in a direction of 35 the length of the applicator-plate 10) and of a substantially-corresponding depth. Under these conditions the succeeding pairs of passages 17c—17d, 17e—17f, and 17g—17h may respectively have dimensions of the character referred to amounting to .0045", .005" and .0056".

Any suitable arrangement of pulleys or rollers (not shown) may be arranged to guide different reaches of the same wire, such as the wire 18, upwardly in succession through the notch-like wire-receiving passages 17a to 17h inclusive to apply to the said reaches successive coatings of a suitable viscous insulating material 19. Preferably, each coating will be thoroughly dried or set before a subsequent coating is applied. It may be here mentioned that it is common and well un-

derstood in the art to apply a series of insulating coatings to a conductor with intervening drying (as by an oven) between coatings.

The particular composition of the insulating material 19 is of no vital import and may for instance consist of suitable synthetic resins or combinations thereof having the desired dielectric strength.

The wire 18, in moving upwardly through a given notch-like wire-receiving passage, will drag up with it a mass of viscous insulating material 19 from a suitable reservoir. The said insulating material (Fig. 4) will swell out into the V-shaped channel in the under face of the assembled applicator-plates 10 and 11 (the said channel being formed by the bevels 15 and 16), but the amount passing completely through the said passages will be determined by the space between the outer periphery of a given reach of the wire 18 and the adjacent boundaries of the wire-receiving passage through which the said reach is moving.

When a wire such as 18 is moving upwardly through a given one of the notch-like wire-receiving passages 17a to 17h, inclusive, the corners of the given passage adjacent the edge of the applicator-plate 11 will not of course be intruded into by said wire. This will result in permitting a greater amount of insulation 19 to move upwardly through the said passage at the locations referred to than will be the case at other portions of the passage where the latter approximates and closely approaches the contour of the wire. The areas free for the upward movement of insulating material 19 may be considered as being of fillet-shape as indicated by the reference characters 20—20 in Fig. 3.

With very viscous insulating materials, the portion thereof passing up through the areas indicated at 20—20, would be likely to cause an uneven coating on the wire since such viscous insulating material has limited capacity for evening itself out in a circumferential direction. In order to compensate for the insulating material 19 moving upwardly through the areas 20—20, it is preferred to form a notch-like compensating-passage 21, in the outer wall of each of the passages 17a to 17h inclusive.

Each of the compensating-passages 21 preferably has a cross-sectional area substantially corresponding to the combined cross-sectional areas of the adjacent fillet-like portions 20—20, so that viscous insulating material will come up through the given passage 21 simultaneously with that portion of the insulating material moving upwardly through the areas 20—20, and when the coated wire has moved upwardly sufficiently beyond the upper face of the complementary applicator-plates 10 and 11, the insulating coating will even itself out and form a coating of substantially uniform depth entirely around the circumference of the wire 18.

By forming a given notch-like passage such as any one of the notches 17a to 17h inclusive, solely in one of the applicator-plates and then closing the lateral boundary of such a passage by the straight portion of the complementary applicator-plate, greater uniformity of coating is secured than would be the case in instances where a given notch-like recess is formed partly in one applicator-plate and partly in a complementary applicator-plate or their equivalents. The pertinency of the statement just made will be apparent if the difficulty of registering two parts of a passage, when the dimensions involved are but a few thousandths of an inch is borne in mind.

Electric wires coated by means of the appli-

cator of the present invention have provided far greater continuity of insulation than it has been possible to produce on applicators at present in use, and at far greater speed. Furthermore, the applicator of the present invention has permitted the use of very viscous coating material thus eliminating the requirement for using large amounts of solvents or diluting materials in order to insure that the coating will be continuous.

10 Very little attention is required by an operator in using the applicator of the present invention and there is negligible, if any, tendency of the insulating material to drip back onto the upper surface of the applicator-plates to thus cause rough surfaces on the wire.

15 The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

20 We claim:

25 1. An applicator for applying viscous insulating material to wire, including in combination: a first portion having an inner edge and a notch-like wire-receiving passage formed in the said inner edge; and a second portion separable from the said first portion and having an inner edge abutting against the said inner edge of the first member and extending uninterruptedly across the open side of the notch-like passage therein and closing the same; the said wire-receiving passage having a wall directed generally toward the abutting inner edge of the said second portion and formed with a compensating-passage communicating laterally with the said wire-receiving passage.

30 2. An applicator for applying viscous insulating material to wire, including in combination: a first applicator-plate having an inner edge and a notch-like wire-receiving passage formed in the said inner edge; and a second applicator-plate separable from the said first applicator-plate and having an inner edge abutting against the said inner edge of the first applicator-plate and extending uninterruptedly across the open side of the notch-like passage therein and closing the same; the said wire-receiving passage having a wall directed generally toward the abutting inner edge of the said second applicator-plate and formed with a compensating-passage communicating laterally with the said wire-receiving passage.

35 3. An applicator for applying viscous insulating material to wire, including in combination: a first applicator-plate having a beveled inner edge and formed in its said inner edge with a notch-like wire-receiving passage; and a second applicator-plate

40 also having a beveled inner edge abutting against the said inner edge of the first applicator-plate and extending uninterruptedly across the open side of the notch-like wire-receiving passage therein to close the same; the said wire-receiving passage having a wall directed generally toward the abutting edge of the said second applicator-plate and formed with a compensating-passage communicating laterally with the said wire-receiving passage.

45 4. An applicator for applying viscous insulating material to wire, including in combination: a first applicator-plate having a longitudinally straight inner edge and formed in its said inner edge with a plurality of spaced-apart notch-like

wire-receiving passages; and a second applicator-plate also having a longitudinally-straight inner edge abutting against the said inner edge of the first applicator-plate and extending uninterruptedly across the open side of each of the plurality of notch-like wire-receiving passages therein to close the same.

5. An applicator for applying viscous insulating material to wire, including in combination: a first applicator-plate having a longitudinally-straight beveled inner edge and formed in its said edge with a plurality of spaced-apart notch-like wire-receiving passages; and a second applicator-plate also having a longitudinally-straight beveled inner edge abutting against the inner edge of the first applicator-plate and extending uninterruptedly across the open side of each of the plurality of notch-like wire-receiving passages there-

10 in to close the same; each of the said wire-receiving passages having a substantially semicircular wall directed toward the abutting edge of the said second applicator-plate and formed with a compensating-passage communicating laterally with the said wire-receiving passage.
